US0D1108445S

(12) **United States Design Patent** (10) **Patent No.:** **US D1,108,445 S**
(45) **Date of Patent:** **** Jan. 6, 2026**

(54) **ELECTRONIC DEVICE WITH GRAPHICAL
USER INTERFACE**

1/00408-00437; G06T 2200/24; B41J
29/38; G03G 15/5016; G03G 15/502

See application file for complete search history.

(57) **CLAIM**

The ornamental design for an electronic device with graphical user interface as shown and described.

DESCRIPTION

FIG. 1 is a front view of an electronic device with graphical user interface showing the claimed design; and,

FIG. 2 is a front view of an electronic device with graphical user interface of FIG. 1 applied to the display screen.

The outer broken lines in the figures show a display screen or portion thereof, or an electronic device having a display screen, and form no part of the claimed design. The other broken lines in the figures show portions of the graphical user interface that form no part of the claimed design.

FIG. 1

FIG. 2
